UNITED STATES PATENT OFFICE

158,199

DISPENSER FOR CIGARETTE PACKAGES
AND LIKE OBJECTSDavid Kirsch and Nathan Avrashow,
Los Angeles, Calif.

Application October 4, 1948, Serial No. 148,958

Term of patent 14 years

(Cl. D52—2)

To all whom it may concern:

Be it known that we, David Kirsch and Nathan Avrashow, citizens of the United States, residing at Los Angeles, in the county of Los Angeles and State of California, have invented a new, original, and ornamental Design for a Dispenser for Cigarette Packages and Like Objects, of which the following is a specification, reference being had to the accompanying drawing, forming a part thereof, and in which the figure is a front perspective view of a dispenser for cigarette packages and like objects, showing our new design.

The rear of the dispenser is identical in appearance to the front, except that the bottom peripheral shield or guard is continuous.

The stacked packages of cigarettes shown in broken lines are for illustrative purposes only.

We claim:

The ornamental design for a dispenser for cigarette packages and like objects, substantially as shown and described.

DAVID KIRSCH.
NATHAN AVRASHOW.
